S. RADLOWSKI

WINDOW FASTENING DEVICE

Filed March 23, 1927

INVENTOR
Stanley Radlowski
BY
R. L. Radlowski
ATTORNEY

UNITED STATES PATENT OFFICE.

STANLEY RADLOWSKI, OF WARD, WEST VIRGINIA.

WINDOW-FASTENING DEVICE.

Application filed March 23, 1927. Serial No. 177,588.

This invention relates generally to windows, and has more particular reference to a novel means for fastening window panes into frames therefor. The customary old method of accomplishing this purpose makes use of nails and a putty filler. In a short period of time, the putty dries and falls out, and therefore the joint is unsatisfactory.

The invention has for an object the provision of improved means for securing window panes into frames, which is efficient in action, and which can be manufactured and sold at a reasonable cost.

For further comprehension of the invention, and of the objects and advantages thereof, reference will be had to the following description and accompanying drawing, and to the appended claims in which the various novel features of the invention are more particularly set forth.

Referring to the drawing forming a material part of this disclosure:

Fig. 1 is a fragmentary rear view of a window constructed with the invention device.

Fig. 2 is a fragmentary enlarged view of a portion of Fig. 1.

Fig. 3 is a vertical sectional view taken on the line 3—3 of Fig. 2.

Fig. 4 is a view similar to Fig. 3 but of a modified form of the invention.

Fig. 5 is a vertical sectional view taken on the line 5—5 of Fig. 2.

Fig. 6 is a longitudinal vertical sectional view taken on the line 6—6 of Fig. 2.

The reference numeral 10 indicates a window frame, and 11 a window pane associated therewith. Strips of resilient material 12, preferably made of rubber and being of triangular cross-section engage in the corners formed by the pane 11 and frame 10. Other strips of material 13, preferably of metal, cover the strips 12. The strips 12 are formed with recesses 14 at certain portions along their lengths, and strips 13 are formed with apertures 15 aligned with the recesses. Projecting from the strips 13 are tongues 16 housed in the recesses 14, and rollers 17 are supported in the recesses 14 between a pair of these tongues. Each of the rollers

17 are formed with an aperture 18, and nails 19 pass through these apertures at any desirable tilt, obtaining by turning the rollers, and thereafter the nails are driven through the strips 12 into the frame 10. Thus the window pane is securely held in place in the frame, and the rubber strips 12 act to form a waterproof joint, desirable inasmuch as rain cannot pass.

The nails 19 engage the rollers 17 in place, and the rollers being attached to strips 13, hold the strips, which in turn hold the other strips 12. The rollers 17 are turnably mounted, and the nails 19 passed through the apertures 18 of the rollers may be quickly driven into the frame 10 at any tilt.

In the modification of the invention illustrated in Fig. 4 the strip 13' is narrower than the strip 12', and furthermore, is embedded therein.

While I have illustrated and described my invention with some degree of particularity, I realize that in practice various alterations therein may be made. I therefore reserve the right and privilege of changing the form of the details of construction or otherwise altering the arrangement of the correlated parts without departing from the spirit or the scope of the appended claims.

Having thus described my invention, what I claim as new and desire to secure by United States Letters Patent is:

1. In combination with a window frame and associated window pane, a strip of material adapted for engagement in the corners formed by the frame and pane, another strip of material on the said strip, the first mentioned strip being recessed at certain portions along its length, the second mentioned strip being formed with apertures aligned with the recesses, tongues projecting from the second mentioned strip into the recesses, a roller supported in each recess between a pair of the tongues, each roller being formed with an aperture, and nails guided through the last mentioned apertures, and forced into the first mentioned strip and the window frame.

2. A device for securing a pane in place in a window frame, comprising a resilient strip of material adapted for engagement in

the corners formed by the frame and pane, another strip of reinforcing material on the said strip, the first mentioned strip being recessed at certain portions, the second mentioned strip being formed with apertures aligned with the recesses, tongues projecting from the second mentioned strip into the recesses, and a roller supported in each recess between the tongues, the said rollers being formed with apertures. 10

In testimony whereof I have affixed my signature.

STANLEY RADLOWSKI.
